(57) **CLAIM**

The ornamental design for a rain gutter cleaning device with a 180° rotatable blade, as shown and described.

DESCRIPTION

FIG. 1 is a right side perspective view of my design for a rain gutter cleaning device with a 180° rotatable blade showing the new design;

FIG. 2 is another right side perspective view with the 180° rotatable blade in an alternate configuration;

FIG. 3 is a front view of FIG. 1;

FIG. 4 is a rear view thereof;

FIG. 5 is a right side view thereof;

FIG. 6 is a left side view thereof;

FIG. 7 is a bottom view thereof; and,

FIG. 8 is a top view thereof.

The broken lines in the figures depict portions of the rain gutter cleaning device with a 180° rotatable blade that form no part of the claimed design.
